[57] CLAIM

The ornamental design for a vessel jacket, as shown and described.

DESCRIPTION

FIG. 1 is a top, left side, perspective view of a vessel jacket of the present design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom view thereof.

The broken lines are for illustrative purposes only and form no part of the claimed design.
